SLING SHOT PISTOL GRIP

Wilbur J. Watkins, Long Beach, Calif.

Application October 14, 1954, Serial No. 32,669

Term of patent 14 years

(Cl. D34—15)

FIG. 1.

FIG. 2.

FIG. 3.

FIG. 4.

Figure 1 is a top plan view of a sling shot pistol grip, showing my new design;

Figure 2 is a side elevational view thereof;

Figure 3 is a rear elevational view thereof; and

Figure 4 is a front elevational view thereof.

The broken line showing an elastic band and missile holder is for illustrative purposes only.

I claim:

The ornamental design for a sling shot pistol grip, as shown and described.
